UNITED STATES PATENT OFFICE.

ALFRED E. POWELL, OF BRONXVILLE, NEW YORK.

VALVE.

1,402,314.

Specification of Letters Patent.

Patented Jan. 3, 1922.

Application filed March 3, 1921. Serial No. 449,293.

To all whom it may concern:

Be it known that I, ALFRED E. POWELL, a citizen of Great Britain, residing at Bronxville, in the county of Westchester 5 and State of New York, have invented a new and useful Valve, of which the following is a specification.

This invention relates to valves, and more particularly to valves employed in flush 10 tanks, the primary object of the invention being to provide a noiseless gravity controlled valve.

A further object of the invention is to provide means for converting the usual 15 valve now in use, into a valve which may be used in connection with an elevated flush box, of the gravity controlled type, or one which may be used in connection with a relatively low flush box.

20 A still further object of the invention is the provision of means to eliminate a suction of air being created by the water passing through the valve, to render the device inoperative.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

30 Referring to the drawing:—

Figure 1 is a fragmental sectional view through a flush tank, showing a valve constructed in accordance with the present invention, as positioned therein.

40 Figure 2 is a vertical sectional view through the valve.

Figure 3 is a vertical sectional view taken at right angles to Figure 2.

45 Figure 4 is a perspective view of the attachment employed in connection with the valve.

Referring to the drawing in detail, the reference character 5 designates the base of the valve which is provided with a threaded 50 extension 6, and a lateral chamber 7, there being provided an opening in the upper wall of the chamber to accommodate the pipe 8, which usually admits air to the valve.

55 Formed integral with the base 5 is an upper flared portion 9 forming a valve seat

for the ball valve 10, which fits within the mouth of the flared portion 9 to normally prevent fluid from passing through the base.

60

A yoke indicated at 11 extends above the flared portion 9 and is provided with a suitable opening to accommodate the valve stem 12 which has its lower extremity removably connected to the ball valve 10, as at 13, so 65 that the valve member 10 may be readily and easily disconnected to permit of free access to the interior of the base 5.

The attachment, which forms the essence 70 of the present invention includes a tongue 14 having an enlarged portion 15 formed integral therewith, there being provided an upwardly extending right angled flange 16, forming a part of the attachment, to partition the base 5 into a central compartment 75 and a lateral compartment.

As shown, the tongue member 14 lies flush 80 with the upper surface of the bottom of the chamber 7 where the same is held in such position by means of the pin 17 which is carried by the vent pipe 8 and engages the tongue to force the same against the bottom of the chamber 7.

Thus it will be seen that as the valve member 10 is unseated, the water rushing 85 downwardly through the valve and by the deflecting device of flange 16, is caused to be delivered laterally within the chamber 7, where the water rises to a level within the pipe 8 equal to the level of the water within 90 the tank, thereby excluding all air from the tank and permitting the valve to operate by gravity.

It is to be understood that this attachment 95 renders the device absolutely noiseless in operating as a gravity controlled valve.

It might be further stated however that the partitioning member forming the essence of the invention, may be formed integral with the body of the valve during the 100 casting of the valve.

What is claimed as new is:—

1. In combination with a valve body including a lateral chamber and an upper flared portion providing a valve seat, a partitioning member including an enlarged portion, and an integral tongue portion adapted to extend into the lateral chamber, and a right angled flange forming a part of the enlarged portion for dividing the water 110 passing through the body portion.
2. In combination with a valve body in-

- cluding a lateral chamber and an upper flared portion providing a valve seat, a partitioning member including a tongue adapted to be positioned within the lateral chamber, 5 a vent pipe in communication with the lateral chamber, means carried by the vent pipe and contacting with the tongue for securing the partitioning member within the lateral chamber, means forming a part of 10 the partitioning member for directing a quantity of the water passing through the valve to the lateral chamber, and a valve for controlling the passage of water through the body portion.
- 15 3. In a valve construction, a body portion having a valve seat and a lateral chamber, a vent pipe in communication with the lateral chamber, a partitioning member within the lateral chamber, a pin carried by the 20 vent pipe and adapted to contact with the partitioning member for securing the same against movement, said partitioning mem-
- ber adapted to direct a quantity of fluid into the vent pipe, and a valve for controlling the passage of fluid through the body portion. 25
4. In a valve construction, a body portion having a valve seat and a lateral chamber, a vent pipe, a partitioning member positioned within the lateral chamber and having an enlarged portion extending into the body portion for directing a quantity of fluid into the lateral compartment, means carried by the vent pipe for securing the partitioning member against movement, and a 30 valve for controlling the passage of fluid therethrough. 35

In testimony that I claim the foregoing as my own, I have hereto affixed my signature in the presence of two witnesses.

ALFRED E. POWELL.
